J. P. STOFFEL,
CLASSIFIER FOR FLOUR MILLS,
APPLICATION FILED JAN. 11, 1916.

1,223,005.

Patented Apr. 17, 1917.

UNITED STATES PATENT OFFICE.

JOHN P. STOFFEL, OF LOS ANGELES, CALIFORNIA.

CLASSIFIER FOR FLOUR-MILLS.

1,223,005.

Specification of Letters Patent. Patented Apr. 17, 1917.

Application filed January 11, 1916. Serial No. 71,433.

To all whom it may concern:

Be it known that I, JOHN P. STOFFEL, a citizen of the United States, residing at Los Angeles, in the county of Los Angeles and State of California, have invented new and useful Improvements in Classifiers for Flour-Mills, of which the following is a specification.

This invention relates to a classifier for flour mills and particularly pertains to a gyrating sifter and means for vibrating the sifter screens and for directing and regulating the movement of granular material thereover.

15 It is the object of this invention to provide a mechanism for separating and grading the stock and flour obtained by subjecting grain to the crushing action of milling rollers, which embodies a plurality of superposed grading screens or sieves having meshes of such different degrees of fineness and so arranged in relation to each other that the ground materials may be separated into various classes, according to their degree of granulation, such as fine, medium and coarse stocks, and flour.

Another object is to provide an arrangement of the screens in a gyrating sifter which will permit of the ready delivery of the several grades of the granular materials from one screen to another and to separate points of discharge.

The principal object is to provide means for vibrating the sifter screens independent of the movement of the screen in its entirety so as to facilitate the passage of the finer granular materials therethrough and thus serve to prevent clogging of the screen, thereby effecting a rapid screening and separating action.

A further object is to provide adjustable means for controlling the movement of the materials carried on the various screens to prevent the material from accumulating excessively at points on the screen surface and for spreading the coarser materials over the screens in layers not in excess of a predetermined depth.

50 A further object is to provide a shuttle vibrator of simple construction which is automatic in its operation and adapted to be attached to most gyrating or reciprocal sifting screens now generally in use for the purpose of agitating the screens and the materials thereon independent of the screen frames.

Another object is to provide a simple and effective means whereby the distributing flights or spreaders may be adjusted and retained in various positions to regulate the depth of materials on the screens.

Other objects will appear hereinafter.

The invention is illustrated in the accompanying drawings in which:

Figure 1 is a view in section and elevation illustrating the construction of the lateral shuttle vibrator.

Fig. 2 is a view in section and elevation showing the adjustable flight or obstructor.

Fig. 3 is a view in perspective of the shuttle vibrator support and impact member.

Fig. 4 is a view illustrating the shuttle vibrator as mounted on the under side of a screen.

Fig. 5 is an enlarged detail section and elevation illustrating the manner of holding the adjustable flight in various positions.

Fig. 6 is a detail of the stationary obstructors carried by one of the screens.

Fig. 7 is a view in perspective of a modified form of the shuttle vibrator.

The essence of the present invention resides in means for vibrating bolting screens used in flour mill machinery, independent of their frames so as to reduce clogging of the screens to a minimum, and also in flights for regulating the spreading of the materials over the screens.

As the granular character of the materials varies throughout the different screens, it is deemed necessary to provide several forms of vibrators and flights on the different screens according to the nature of the material being worked.

In this case I have illustrated the screens as provided with transverse vibrators, one of

which is shown in detail in Fig. 1. This vibrator consists of a reciprocal shuttle or bar 53 which is slidably supported adjacent its ends in brackets 54 and arranged transversely of the screen.

The brackets 54 are spaced a suitable distance apart and are secured to the screen in any desired manner.

While the brackets may be of various constructions, they are here shown as formed of wire, as illustrated in Fig. 6; the wire being bent to form a spring coil 55 through which the shuttle vibrator 53 slidably extends. The ends of the coil 55 terminate in leg members 56 which are looped at their ends to receive bolts or other fastenings by which the brackets are held in place. The shuttle 53 is of a length greater than the

100

105

110

space between its supporting brackets and its outer ends are fitted with shoulders or stops 57 which serve to retain the shuttle in place and also act as strikers which, on 5 reciprocation of the shuttle will impact against the brackets 54 and thereby vibrate the screens. The reciprocation of the shuttle is effected by the impulse transmitted thereto by the gyrating movement of the classifier.

10 The screen 32 which is of fine mesh, is fitted with longitudinal shuttle vibrators 58, as illustrated in Fig. 3. These vibrators may be mounted upon brackets 54 as shown in Fig. 1 if desired, but are here illustrated in 15 Fig. 3 as carried by stationary flights 59 which are secured to the screen 32 and extend transversely thereof. The longitudinal shuttles 58 are slidably carried by the flights 59 and are of such length as to be capable 20 of reciprocal movement in relation to the flights so that when they are moved longitudinally by the impulse given thereto by movement of the classifier, shoulders 60 on the ends of the shuttles 58 will strike the 25 flights 59 with sufficient force to vibrate the screen 32. While I have shown the vibrators as arranged above the screens, it is manifest that they may be disposed on the under side thereof, as illustrated in Fig. 4 and while 30 the vibrators are shown as extending transversely and longitudinally of the screens it is obvious that they may be placed to extend diagonally and that their number and arrangement may be varied as occasion 35 requires.

It is to be noted that the brackets or supports for the shuttle vibrators are attached to the screen and not to the screen frames so that the force of impact of the shuttles is 40 delivered to the screens independent of their frames.

The adjustable flights shown on the screen are illustrated in detail in Figs. 2 and 5. The flights consist of depending blades or 45 plates 61 which are rigidly mounted on stems 62, reciprocally and revolvably mounted in the frames. The outer ends of the stems 62 project beyond one of the side rails of the screen frames and are formed with 50 hand-holds 63 by means of which they may be shifted longitudinally or turned laterally. As a means for normally maintaining the stems 62 in their outermost position, collars 64 are formed on the stems and springs 65 55 arranged to bear between the collars and a stationary part of the frame. The plates 61 forming the flights extend within a short distance of the upper faces of the screens when the flights are in their normal vertical 60 position. When it is desired to adjust the spacing between the flights and the screen the stem 62 is moved inwardly and turned in either direction to dispose the flight in the

desired position. The stem is then retracted to position the flight blade between a pair of 65 spaced pins 66 on the screen frame, as shown in Fig. 5, which pins, in engaging the opposite sides of the flight blade, serve to hold the latter against turning movement. The spring 65 then operates to maintain the 70 flight in engagement with the pins.

The number and arrangement of the flights may be varied as circumstances demand and they may be used in conjunction with stationary flights if desired. 75

In the movement of the granular materials across the several screens, they are caused to have a spiral path of travel, and therefore have a tendency to accumulate 80 along one wall of the screen frame or its partition. The flights are provided for preventing this accumulation and also to cause the materials to spread evenly over the screens at a depth not exceeding a predetermined point; the depth of the layer of materials on the screens being regulated by adjusting the flights. The gyratory movement of the classifier operates to reciprocate the shuttle vibrators which on striking their supports transmit a vibrating shaking action 85 to the screens, tending to loosen such particles of the granular materials as clog the screen mesh, thus hastening the action of the classifier and lessening the amount of attention ordinarily required in maintaining the 90 screens clean. 95

In Fig. 7 I have illustrated a modified form of the shuttle vibrator and brackets, the latter being formed with wire and having a pair of loops 67 arranged side by side and the shuttle bar consisting of wire bent to return on itself to pass through the loops. In this construction the bend 68 of the wire forms a shoulder which strikes the brackets on reciprocation of the shuttle. 100

While I have shown the screens as divided longitudinally, it is manifest that such division may be dispensed with in some instances. It is obvious that various changes may be resorted to and the parts differently 110 arranged in relation to each other without departing from the spirit and scope of the invention as set forth in the following claim.

What I claim is:

In a classifier, a screen, a pair of spaced brackets affixed to said screen, a bar reciprocally mounted in said brackets, and shoulders on the outer ends of said bar adapted to alternately strike said brackets on reciprocal movement of the bar, said bar being adapted to be reciprocated on shaking of the screen. 120

In testimony whereof I have signed my name to this specification.

JOHN P. STOFFEL.
